UNITED STATES PATENT OFFICE.

JOHN H. OWENS, OF HILLSBOROUGH, TEXAS.

CULTIVATOR.

SPECIFICATION forming part of Letters Patent No. 611,437, dated September 27, 1898.

Application filed April 25, 1898. Serial No. 678,775. (No model.)

To all whom it may concern:

Be it known that I, JOHN H. OWENS, a citizen of the United States of America, residing at Hillsborough, in the county of Hill and State of Texas, have invented certain new and useful Improvements in Cultivators, of which the following is a specification, reference being had therein to the accompanying drawings.

10 This invention relates to improvements in cultivators, and has for its object the provision of novel means for adjusting the central cultivator-beam carrying the foot or standard to which is secured the shovel transversely of the cultivator. Furthermore, the object of the invention is to produce a cultivator in which the "fifth foot" or central shovel can receive the adjustment above set forth independent of the longitudinal beams 20 forming the frame.

The invention consists in the details of construction and in the arrangement and combination of parts to be hereinafter more fully set forth and specifically claimed.

25 In describing the invention in detail reference is had to the accompanying drawings, forming part of this specification, wherein like characters of reference denote corresponding parts in the several views, in which—

30 Figure 1 is a top plan view of a cultivator with my invention applied thereto. Fig. 2 is a detail view, partly in section, of the adjusting mechanism. Fig. 3 is a perspective view of one of the standards. Fig. 4 illustrates a 35 modified mode of assembling the parts.

In the drawings I illustrate a cultivator-frame consisting of two parallel longitudinal beams 1, to which are secured in any suitable manner shovels 2. Transversely of the 40 frame I arrange a beam 3, mounted to reciprocate therebetween, and depending from the beam centrally thereof I arrange a shovel 4. Each end of the beam is provided with an eye 5, which receives a standard 6, said standard having a shoulder 7, which limits its 45 downward movement. Each standard is cranked, as at 8, so that a manipulation

thereof will operate the beam, as stated. A movable collar 9 is also provided for each standard and is made adjustable thereon for 50 the purpose of allowing the standard to be set in a ring or socket 10, attached to the cultivator-frame.

From the foregoing description it will be understood that when the cultivator is used 55 in rows which are crooked it will only be necessary for the operator to exert pressure on the fifth foot on one side or the other, and by reason of the cranked standards the beam can be thrown from side to side.

60 While some users may prefer to have a handle connected to the beam or fifth foot for manipulating the parts, I have found in practice that sufficient pressure can be exerted by the foot of the operator. I have also found 65 that this manipulation can be accomplished without the loss of time.

The construction, operation, and advantages will, it is thought, be understood from the foregoing description, it being noted that 70 changes in the proportions and other details of construction may be made without departing from the spirit of the invention. For instance, the parts may be assembled as illustrated in Fig. 4, when the pressure for manipulating the parts would be exerted on the lower end of the standard, while in the construction shown in Fig. 2 the adjustment is accomplished by pressure on the upper end.

75 Having fully described my invention, what 80 I claim as new, and desire to secure by Letters Patent, is—

In combination with a plow-frame, a transverse beam having an eye formed at each end, cranked standards each having one end fitting 85 in bearings of the frame, the upper ends of the standards fitting in the eyes of the beam, as and for the purpose described.

In testimony whereof I affix my signature in the presence of two witnesses.

JOHN H. OWENS.
